WIRE ARTICLE

Joseph Lapinskas, Cicero, Ill.

Application November 10, 1937, Serial No. 173,929

3 Claims. (Cl. 245—1)

The present invention relates to new and useful improvements in wire articles and has for one of its important objects to provide, in a manner as hereinafter set forth, a device of this character which is capable of assuming various novel shapes and which is adapted for a number of different uses, such as a basket or receptacle, a support, etc.

Another important object of the invention is to provide a wire article of the aforementioned character embodying a novel construction and arrangement of bottom or base.

Still another very important object of the invention is to provide, in a wire article of the type comprising upper and lower units including swinging loops, novel means for connecting said loops together for operation in unison.

Other objects of the invention are to provide a wire article of the character described which will be comparatively simple in construction, strong, durable, highly efficient and reliable in use, compact, light in weight, attractive in appearance and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is an elevational view of an embodiment of the invention.

Figure 2 is a plan view of the bottom or base of the article.

Figures 3 to 6, inclusive, are phantom views illustrating a number of different shapes which the article is capable of assuming.

Figure 7 is a fragmentary view in perspective, showing a portion of the bottom or base.

Referring now to the drawings in detail, it will be seen that the embodiment of the invention which has been illustrated comprises upper and lower units which are designated generally by the reference numerals 1 and 2, respectively. The lower unit 2 includes a ring 3 of suitable heavy wire having formed therein at spaced points depending loops constituting supporting legs 4. Mounted diametrically on the ring 3 and secured at their ends thereto are supporting wires 5. As illustrated to advantage in Figs. 1 and 7 of the drawings, certain of the wires 5 are wrapped around and secured to the neck portions of the loops 4, as at 6, in a manner to strengthen said loops 4. Where they cross, the wires 5 are se-

cured together in any suitable manner, as at 7. Spaced, concentric wire rings 8 are mounted on the wires 5. Journalled on the ring 3 for swinging movement in a vertical plane is a plurality of wire loops 9 which are preferably of substantially the shape shown to advantages in Fig. 1 of the drawings. The loops 9, it will be noted, are slidably interconnected for operation in unison. On their free ends the loops 9 are twisted in a manner to form eyes 10.

The upper unit 1 of the article comprises a ring 11 of suitable heavy wire. Journalled on the ring 11 for swinging movement in a vertical plane are what may be referred to as upper and lower series of wire loops 12 and 13, respectively. It will be noted that the loops 12 and 13 are also slidably interconnected for operation in unison. Further, loops 13 are twisted on their free ends in a manner to provide eyes 14 which are engaged in the eyes 10 thus connecting said loops 13 to the loops 9 for operation therewith.

On their free ends the upper loops 12 are formed to provide eyes 15. Mounted in the eyes 15 is an endless chain or other suitable flexible element 16 which may be utilized for supporting the article as well as for drawing the loops 12 inwardly. Threaded through the eyes 10 on the loops 9 is an endless flexible element in the form of a ribbon, wire or the like 17 which, in addition to being ornamental, may limit the spread of said loops and support them in open position.

It will thus be seen that a wire article of attractive appearance has been provided which is capable of assuming a large number of different shapes, such as those illustrated in Figs. 3 to 6, inclusive, of the drawings. While the device is intended primarily for use as a basket or receptacle, it is adapted for many other uses, such as a support for various articles. When in a completely collapsed or folded position the device will occupy a minimum of space.

It is believed that the many advantages of a wire article constructed in accordance with the present invention will be readily understood and although a preferred embodiment of the device is as illustrated and described, it is to be understood that changes in the details of construction may be resorted to which will fall within the scope of the invention as claimed.

What is claimed is:—

1. An article of the class described comprising upper and lower units, the lower unit including a wire supporting ring, a plurality of slidably interconnected loops journalled on said supporting ring for swinging movement in a vertical plane,

the free ends of said loops being formed to provide eyes, an endless flexible element mounted in said eyes, the upper unit comprising a wire ring, slidably interconnected loops journalled on the second named ring for swinging movement in a vertical plane, the free ends of said second named loops being formed to provide eyes engaged in the first named eyes for connecting the first and second named loops together for operation in unison.

2. An article of the class described comprising operatively connected upper and lower foldable units, said lower unit comprising a wire ring including depending loops at spaced points providing supporting legs, and a plurality of wires

mounted diametrically on said ring, the end portions of certain of said wires being wrapped around and secured to the neck portions of said loops.

3. An article of the class described comprising upper and lower units, each unit including a ring and slidably interconnected loops journalled on said ring, means operatively connecting the loops of the lower unit to certain of the loops of the upper unit for operation in unison therewith, eyes on the free ends of the remaining loops of the upper units, and an endless flexible element mounted in said eyes and constituting a support for the article.
